UNITED STATES PATENT OFFICE.

SAMUEL V. REEVES, OF HADDONFIELD, NEW JERSEY.

HOT-WATER STOVE.

1,190,460.

Specification of Letters Patent. Patented July 11, 1916.

Application filed July 2, 1913. Serial No. 776,894.

To all whom it may concern:

Be it known that I, SAMUEL V. REEVES, a citizen of the United States, residing at Haddonfield, county of Camden, State of New Jersey, have invented a new and useful Hot-Water Stove, of which the following is a specification.

My present invention relates to a hot water stove which is adapted to be used on water pressure systems as well as on closed and open tank gravity systems.

With the above in view, my invention in its broad and generic scope, consists of a novel construction of a heating stove, where- 15 in is employed a novel type of water jacket.

It further consists of a novel construction of a water jacket or cored chamber, which may be rotatably adjusted in order to make the proper connections therewith.

20 It further consists of a novel construction of a stove of the character described, in which a core or jacket of novel construction is employed, whereby a maximum amount of water is heated with a minimum consump- 25 tion of fuel.

It further consists of a novel construction of a water jacket wherein the water chamber has a lesser internal diameter near the grate line than it has for a predetermined 30 distance above the grate line.

It further consists of a novel construction of a water jacket wherein the outer wall of the water chamber is at an angle to the inner wall thereof.

35 It further consists of other novel features of construction, all as will be hereinafter fully set forth.

For the purpose of illustrating my invention, I have shown in the accompanying 40 drawing a typical embodiment thereof which is at present preferred by me, since the same has been found in practice to give satisfactory and reliable results, although it is to be understood that the various instrumentalities of which my invention consists can be 45 variously arranged and organized and that my invention is not limited to the precise arrangement and organization of these instrumentalities as herein shown and de- 50 scribed.

The accompanying drawing represents an elevation, partly in section, of a heating stove embodying my invention.

Similar numerals of reference indicate 55 corresponding parts in the figures.

Referring to the drawings: In heating

stoves of small size, wherein the water chamber of the jacket is of uniform diameter, considerable difficulty has arisen in maintaining the fire owing to the large volume of 60 water surrounding the fire which tends to deaden the same. In former devices it has been deemed necessary to construct the fire chamber beneath the water jacket the result of which is that the heat which should be 65 imparted to the water is radiated into the room. In accordance with my present invention, the water jacket is cored into close proximity with the grate line and has a lesser diameter at such point than is given 70 to the water jacket at a point located above the bed of fuel. The stove, base, and the grate may be of any desired or conventional construction, and the top may also vary 75 widely in practice, and in the present instance, I have shown the base portion 1 supported in any desired manner and provided with a laterally extending annular flange 2 and a grate 3, which latter is supported on a shoulder 4 formed within the base. 80

5 designates the water jacket which in Fig. 1 is provided with an inner cylindrical wall 6, illustrated as substantially vertical and having formed therewith an outer wall 7, which latter is outwardly deflected toward 85 its central point to form angularly inclined sides which are united at 9, at which point the water jacket chamber has its greatest internal diameter.

10 designates a conduit communicating 90 with a source of water supply, such as for example, a water pressure system or a closed or open tank gravity system, it being understood that the water may pass through the conduit 10 under any desired pressure, said 95 conduit communicating with the interior of the water jacket near the lower end thereof.

11 designates a discharge conduit communicating with the upper part of the internal chamber thereof and leading to a desired point of utilization. The water jacket, at its lower end, is provided with a laterally extending lug 12, which is connected with the flange 2 of the base by means of fastening devices 13 of any desired or conventional 105 type.

The inner bore of the water jacket 5 at its upper end may be outwardly flared, as at 14, and may be recessed on its outer periphery to form an annular shoulder 15 adapted to 110 support a top casing 16 having any desired contour and which, in the present instance,

is provided with a sectional cover 17 having portions 18 thereof adapted to be removed in the well known manner. The cover 17 is also provided with a collar 19 to which is connected in the usual manner a smoke-pipe through which the unconsumed products of combustion pass from the stove to the chimney or other desired point of discharge. It will thus be seen that the water jacket in Fig. 1 has the formation of a double V-shaped core with the open ends of the V united so that the greatest internal diameter of the water jacket is intermediate the ends thereof. If desired, the outer wall of the water jacket may be provided with radiating ribs 20.

I have disclosed a water jacket, the internal diameter of the water chamber of which is lesser near the grate line than it is above the bed of fuel and which for a predetermined distance above the grate line gradually increases. It will be understood by those skilled in this art that I provide the largest volume of water at the point at which the greatest amount of heat is produced by the bed of fuel.

Water jackets constructed in accordance with my invention, as herein disclosed, have given marked and advantageous results, in practice, and it is possible to heat a very large amount of liquid with a very small amount of fuel. In stoves constructed in accordance with my invention, the circulation is much more rapid than is the case when a water jacket with straight walls is employed, thereby not only largely increasing the efficiency but rendering possible the easy maintenance of a fire of the smallest size. In devices of this character as heretofore constructed, considerable difficulty has arisen in maintaining a fire in hot water stoves of small size, such as for example twelve inches or less in diameter and by the employment of my present invention this difficulty has been wholly overcome.

I am aware that it has heretofore been proposed to employ in a domestic boiler a conical fire pot having a water chamber therearound whose greatest diameter is placed nearest the upper end thereof and in conjunction with which there is employed a conical damper to divide the outgoing products of combustion. My present invention is differentiated therefrom since I employ a water jacket wherein the inner surface thereof is of substantially uniform diameter while the outer wall of said jacket has its greatest diameter at the medial point equidistant from the top and bottom, the upper, outer, annular wall of said jacket converging upwardly from said medial point and the lower, outer, annular wall thereof converging downwardly from said medial point, the inclination of said upper and lower walls with respect to the longitudinal axis of my novel jacket being substantially the same.

By reason of the foregoing construction, it will be apparent that the hottest portion of the fire will be at about the middle of the water jacket, where the area of the body of the water is transversely the greatest, the cooler portions of the fire-pot being at the bottom and at the top where the body of the water is of less transverse area, and by my novel construction, the upper end of the water jacket will be heated to the desired extent by radiant heat, and the circulation of the water will be accelerated to a greater extent than is possible in any of the prior art devices with which I am familiar.

By my novel construction, I avoid a trapped or retarded circulation of the water, which results in a strained or fractured water jacket, since in my device, the circulation is so rapid that there is but one determinate temperature in the whole water chamber, whereas in the prior art devices to which I have referred, there would be three separate and distinct temperatures of the water, the result of which would be to tend to retard the movement or circulation of the water.

It will now be apparent that I have devised a novel and useful construction of a hot water stove which embodies the features of advantage enumerated as desirable in the statement of the invention and the above description, and while I have, in the present instance, shown and described those preferred embodiments thereof which have been found in practice to give satisfactory and reliable results, it is to be understood that the same are susceptible of modification in various particulars without departing from the spirit or scope of the invention or sacrificing any of its advantages.

Having thus described my invention what I claim as new and desire to secure by Letters Patent, is:—

1. In a device of the character stated, a water jacket for a fire-pot, having its interior of uniform diameter and unobstructed, the outer wall of said jacket having its greatest diameter at a medial point equidistant from its top and bottom, and the upper, outer, annular wall of said jacket converging from said medial point upwardly toward said top, and the lower, outer, annular wall thereof converging downwardly from said medial point toward said bottom, the inclination of said upper and lower walls with respect to the longitudinal axis of said jacket being the same.

2. In a device of the character stated, a water jacket for a fire-pot, having its interior of uniform diameter and unobstructed, the outer wall of said jacket having its greatest diameter at a medial point equidistant from its top and bottom, and the

upper, outer, annular wall of said jacket converging from said medial point upwardly toward said top, and the lower, outer, annular wall thereof converging 5 downwardly from said medial point toward said bottom, the inclination of said upper and lower walls with respect to the longitudinal axis of said jacket being the same, a support for said water jacket, a grate car- ried by said support in close proximity to 10 the lower water line of the jacket, and a top casing extending outwardly therefrom and supported above said water jacket.

SAMUEL V. REEVES.
